(57) **CLAIM**

The ornamental design for an ammunition holder, as shown and described.

DESCRIPTION

FIG. 1 is an upper front perspective of an ammunition holder embodying my design;

FIG. 2 is a lower front perspective of the ammunition holder shown in FIG. 1;

FIG. 3 is an upper rear perspective of the ammunition holder shown in FIGS. 1 and 2;

FIG. 4 is a lower rear perspective of the ammunition holder shown in FIGS. 1-3;

FIG. 5 is a front elevation of the ammunition holder shown in FIGS. 1-4;

FIG. 6 is a side elevation of the ammunition holder shown in FIGS. 1-5, with the opposite side elevation being a mirror image thereof;

FIG. 7 is a top view of the ammunition holder shown in FIGS. 1-6;

FIG. 8 is a bottom view of the ammunition holder shown in FIGS. 1-7; and,

FIG. 9 is a rear elevation of the ammunition holder shown in FIGS. 1-8.

1 Claim, 5 Drawing Sheets
